UNITED STATES PATENT OFFICE.

MELBOURNE C. BURR, OF MINNEAPOLIS, MINNESOTA.

CARRIAGE-JACK.

SPECIFICATION forming part of Letters Patent No. 226,971, dated April 27, 1880.

Application filed January 20, 1880.

To all whom it may concern:

Be it known that I, MELBOURNE CLINTON BURR, of Minneapolis, in the county of Hennepin and State of Minnesota, have made certain new and useful Improvements in Carriage-Jacks, which improvements are fully set forth in the following specification and accompanying drawings, in which—

Figure 1 is a side elevation with the jack lowered. Fig. 2 is a side elevation with the jack elevated, and Fig. 3 is a front elevation of Fig. 1. Fig. 4 is a plan view of Fig. 1. Fig. 5 is a front elevation, and Fig. 6 is a rear elevation, of a portion of a jack, showing variations in its method of construction.

This invention relates to carriage-jacks; and it consists in the arrangement of the chocks and lifting-lever whereby a toggle or knuckle joint is formed between the two, and in a curved slot in the chock, whereby it may be kept in its proper position in relation to the lever without the use of connecting bolts or straps, as set forth.

A is the base or foot, upon either side of which two uprights or standards, B, are bolted. Between these standards a chock, C, having the usual notches *a* for supporting the axle, is held by bolts *b*, *b*² passing through holes in the standards and slots *c*, *c*² in the chock.

D is a lever, fulcrumed at *d* by a bolt passing through the standards, and provided with a lip, *e*, which is rounded to fit beneath the lower rounded end, *e*², of the chock C. The rear side of the chock will be so arranged that it will act as a stop to the lever when the chock is down, while the point *e*², when the chock is elevated, will be past the fulcrum *d*, (see Fig. 2,) so that the chock is self-locking, the pressure then coming on the long arm of the lever, and the lower end of the curved slot acting as a stop to its further progress in a backward or downward direction. The upper slot, *c*, will

run at an angle to the standard B, while the lower slot, *c*², will be curved, as shown, in such a line as to cause the lower point, *e*², of the chock to remain in one place on the lip *e*, so that no bolts or straps are required to hold the lever and chock together, they both retaining their same relative positions at all points of the stroke of the lever.

The tops of the notches *a* will be convex, as shown, to cause the chock to roll beneath the axle as it is raised, and thus avoid unnecessary friction.

The sizes of the wheels of vehicles vary so much that it is very difficult to adapt one jack to all. Hence I propose leaving the chocks without the notches *a* being formed in them, so that the purchaser may himself cut the notches in to fit his own vehicle, as shown in Fig. 5.

The curved slot *c*² is a very important feature of my invention, as it enables me to dispense with all bolts, straps, &c., to connect the lever and chock.

The upper slot, *c*, may be replaced by metal straps *h*, as shown in Figs. 5 and 6, if preferred.

Having thus described my invention, what I claim as new, and desire to secure by Letters Patent, is—

The pivoted lever D, having the lip or step *e*, in combination with the chock C, having the slots *c*, *c*², one of which is curved in a line to cause the point *e*² of the chock to retain the same relative position at all points of the stroke of the lever, as set forth.

In testimony whereof I have hereunto set my hand in the presence of two subscribing witnesses.

MELBOURNE CLINTON BURR.
